UNITED STATES PATENT OFFICE.

JOHN F. OHMER, OF DAYTON, OHIO, ASSIGNOR TO OHMER FARE REGISTER COMPANY,
OF DAYTON, OHIO, A CORPORATION OF NEW YORK, (INCORPORATED IN 1902.)

HAND AND FOOT OPERATING MECHANISM.

1,111,172.

Specification of Letters Patent. Patented Sept. 22, 1914.

Application filed October 7, 1912. Serial No. 724,274.

To all whom it may concern:

Be it known that I, JOHN F. OHMER, a citizen of the United States, residing at Dayton, county of Montgomery, and State 5 of Ohio, have invented certain new and useful Improvements in Hand and Foot Operating Mechanism, of which I declare the following to be a full, clear, and exact description.

10 This invention relates to hand and foot operating mechanism for fare boxes and like machines.

The object of this invention is to produce a simple and efficient mechanism of this character 15 so arranged that the time and energy required by a conductor in collecting and registering fares of different values and classes and in making change is a minimum.

The preferred form of fare box employed 20 comprises a table on which the passenger places the fare rather than in the fare hopper as in the boxes now in common use.

In operation the passenger places his fare on the table and the conductor pushes it 25 into the proper compartment of the hopper.

A continued movement of the conductor's hand in the same direction brings it into contact with the proper device to register the fare corresponding to that particular 30 hopper. Mechanisms are also provided by which the conductor may operate the registering device by his foot if he so desires. The conductor, as he finds it necessary, can open the upper drawer and remove from it 35 the cash collected and, after sorting it, place it in the lower drawer for the purpose of making change. The above arrangement permits the conductor to have complete control of fares collected both before and after 40 they are deposited in the fare box, and enables him to make the registrations and change readily and rapidly.

Figure 1 is an elevation of the fare box and its pedestal partly in section showing 45 details of the fare box proper and the register operating mechanism. Fig. 2 is a horizontal section showing details of the fare hopper. Fig. 3 is a perspective view showing details of the means for connecting

and disconnecting the foot pedals with the 50 register operating mechanism.

The fare box is provided with a fare hopper having compartments 6, 7 and 8.

76 is a shield pivotally mounted at 77 and extending over the compartments 7 and 55 8 to prevent metal fares being thrown in said compartments.

Compartment 6 of the fare hopper is provided with an angle plate 4 and a second angle plate 5 of the fare box and forming a 60 guide for the fares deposited. The bottom of compartment 6 of the fare hopper has closure 9 normally held in position to close this compartment by means of spring 10. This closure may be opened to permit fares 65 to be dropped from compartment 6 of the hopper by means of handle 11.

Beneath the fare hopper is a sliding drawer 13 provided with suitable compartments. In the lower part of the box proper 70 is pivoted a drawer 16.

21 designates an angular lever or operating handle which is suitably fulcrumed at the rear of the box. There is one of these operating handles associated with each register mechanism. These handles each operate separate registering mechanisms contained in casing 25. This casing 25 comprises a fare registering mechanism exactly similar to that disclosed in previous patents 75 80 to the applicant, for example, see patent to John F. Ohmer, No. 646,757, April 3, 1900. As the details of this mechanism are not involved in the present invention, no detailed description of the same will be made. 85 Casing 25 is connected to the fare box proper by means of projection 74 carried by casing 25, fitting into hook 75 carried by the fare box proper, and a pin 71 carried by the fare box proper, fitting into a bearing 72 90 carried by the casing 25 and having an oblong slot into which wedge shaped pin 73 can be fitted.

The connections between handles 21, and the registering mechanism contained in casing 25 are all exactly similar, and a detailed description of but one of these connections will be given. Handle 21 comprises a lever,

the lower arm 26 of which extends through the body portion of the fare box and has its lower end formed in a yoke 27 which fits over a lug 28 projecting from slide 29 carried by the casing 25. The slide 29 has formed thereon a yoke 30 fitting over a pawl 31 operating a ratchet 32, which operates the register wheels through gearing 33. The lower arm 26 of lever 21 has a projection 68 5 forming a ratchet which coöperates with a spring controlled pawl 69 forming a full stroke mechanism for handle 21. There is also provided, indicated at 70, an interlocking mechanism for preventing more than one 10 of the handles being operated at the same time. As any common key interlocking mechanism may be used in this connection, detailed description of the interlock for the handles is not deemed necessary.

15 The lower end of lever 26 is provided with a pin 34 to which is pivotally connected a link 36. The lower end of link 36 forms a yoke 37 which fits over a pin 38 carried by a link 39. Pin 38 is frictionally 20 held in yoke 37 by means of a spring pressed plunger 40 carried in a bracket 41 fastened to the body portion of the link 36. Pivotally connected to the lower end of link 39 is a lever 42 carrying foot pedal 43 and 25 pivotally mounted in bracket 45 attached to foot 46 of pedestal 47 carrying the fare box proper. Link 39 is moved to be connected and disconnected from yoke 37 by means of a sliding plate 49 having slots 48 through 30 which passes the lever 39. Plate 49 slides in a bracket 52 mounted on the pedestal 47 and is provided with a handle 51 and a pair of notches 53 coöperating with a plunger 54 for holding plate 49 either in a position in 35 which link 39 is connected with the link 36 or disconnected therefrom. The upper portion of pedestal 47 forms a yoke 55 which acts as a support therefor.

40 If the conductor desires to use the foot 45 pedals in operating the registering mechanism, he grasps handle 51 and through it connects links 36 and 39. The box is now ready for operation without further adjustment. The passenger places his fare on 50 the table 2 and the conductor drops the fare into its proper compartment 6, 7 or 8 as the case may be. In the case of any paper fares, they will drop immediately from the hopper into their proper compartment. 55 In the case of cash or metal fares, however, the fare will first fall upon the closure 9 and can be inspected by the conductor through the openings 65 in the fare box proper, thus permitting him to detect readily the use of slugs or other counterfeit fares. 60 After inspecting the fares he may permit them to be dropped into the cash compartment of box 13 as he desires by moving the closure 9 against the tension of spring 10 by means of the handle 11. The fare, having been dropped into the proper compartment of the drawer or hopper, continued movement of the hand of the conductor will cause the proper handle 21, to be operated and thus operate the proper registering mechanism contained in casing 25. Due to the full stroke mechanism and the interlocking mechanism but one handle can be operated at a time and this handle must be fully operated. This insures that but 65 one fare is registered and that a fare is registered on every operation of the machine. If the conductor so desires, he may operate the registering mechanism through means of pressing the proper one of the 70 foot pedals 43, and thus leave his hands free for the collection of fares or other supervision of the car that may be necessary. The pivotally mounted drawer 16 is kept open while the box is being used and into 75 the compartments 17 of this drawer are placed coins of different denominations for the purpose of readily making change. This arrangement places the cash at a convenient position relative to the register 80 mechanism and causes a considerable saving of time over those methods at present in use.

Having thus fully described my invention, what I claim is the following:

1. In combination, a hand-operative member comprising a bell-crank lever, a foot-operative member including a vertical link bar, a link bar pivoted to the forward end of the hand-operative member and adapted to be freely connected to and disconnected from the vertical link bar of the foot-operative member, and a horizontally slidable plate member engaging the said vertical link bar and adapted to actuate the same in effecting such connection or disconnection. 95
2. In combination, a hand-operative member including a bell-crank lever, a foot-operative member, a connection between said bell-crank lever and said foot-operative member comprising link bars pivoted respectively to the forward arm of said bell-crank lever and the forward end of said foot member, said link bars having a detachable connection at their adjacent ends, 100 a horizontal slide engaging one of said link bars and controlling said connection and means engaging the forward end of said bell-crank lever and compelling a full operative movement thereof. 110
3. In combination, a hand-operative member comprising a bell-crank lever, a foot-operative member, a link bar depending from the forward end of said hand-operative member, and having its lower end 115 terminated in a yoke, a vertical link bar extending from said foot-operative member, a pin on said last named link bar over which 120
- 125

the yoke fits and thus forms a connection between the said link bars, means for maintaining a frictional engagement between said pin and yoke, and a slidable plate engaging one of said link bars and adapted to effect a connection or disconnection between the same.

In testimony whereof I affix my signature in the presence of two witnesses.

JOHN F. OHMER.
